MULTIPLE FURNACE

Carl I. Hayes, Cranston, R. I., assignor to Harold C. Field, Providence, R. I.

Application October 2, 1929, Serial No. 396,716
Renewed April 25, 1932

15 Claims. (Cl. 263—36)

My present invention relates to heat treating, and has particular reference to a method and an apparatus suitable for the multiple heat treatment of metals.

5 One object of my invention is to provide a novel method of multiple heat treatment under controlled atmospheric conditions.

Another object is to provide a novel apparatus for multiple heat treatment which permits the 10 sequence of treatments to be carried out without exposure of the treated material to the surrounding atmosphere.

A further object is to provide an improved apparatus which simplifies multiple heat treatment 15 while facilitating the continuous inspection and supervision of the treated material.

An additional object is to provide an improved apparatus for heat treatment, including a plurality of chambers which are maintained under 20 predetermined atmospheric conditions.

Still another object is to provide an improved apparatus comprising a plurality of chambers each of which may have individually controlled 25 atmospheric conditions therein.

These and other objects and advantageous 30 features will be readily apparent from and will be more fully described in the detailed description following, in conjunction with the accompanying drawings, and will be particularly pointed out in the appended claims:

In the drawings:

Fig. 1 is a perspective view of the novel multiple furnace;

Fig. 2 is a central horizontal section of Figure 1;

Fig. 3 is a vertical section on the line 3—3 of Figure 2; and

Fig. 4 is a section similar to Figure 2, showing 40 individual combustion chambers and nozzle slots for the individual furnaces.

The multiple heat treatment of high speed 45 steels and the like has usually included a preliminary heat treatment at a relatively low temperature, and a high temperature heat treatment followed by quenching in oil or the like. These steps, and similar further steps when required, have heretofore been carried out in different furnace chambers, necessitating transfer of the treated material through the surrounding atmosphere and resultant oxidation. I have devised 50 a novel method and apparatus for multiple heat treatment, which utilizes separate furnace chambers for each step, the chambers communicating with each other to permit free transfer of the material to be treated, and the atmospheric con-

ditions in each chamber and in the communicating passageways being positively controlled to exclude outside atmospheric air and to maintain an enveloping atmosphere for the treated material of a predetermined constituency; and the following is a detailed description of a specific arrangement which embodies the principles of my invention;

Referring to the drawings, the multiple furnace 10 includes a preliminary heat furnace 11, a high temperature furnace 12, and an enclosed passageway 13 which joins the two furnaces and forms an intermediate chamber communicating the throats 14 and 15 of the furnace chambers.

Each furnace chamber, as shown in Figure 3, is heavily insulated with insulating material 16, and is provided with a plurality of heating elements 17, preferably of the electrical resistance bar type. The furnaces may be suitably mounted in any desired manner, the preferred mounting 20 utilizing the corner angle bars 18, which rigidly tie the sides of the furnace together, to support the furnace.

The communicating passageway 13 has an opening 19 in the floor thereof, the opening having a downwardly depending flange 20 which fits into and extends below the surface of a quenching tank 21 equipped with the usual work receiving baskets 22. The tank 21 extends out below the passageway 13, as shown in Figure 1, to be 30 readily accessible to the operator.

The passageway 13 has a door or entrance opening 23 at the front thereof, the floor of the opening having a narrow longitudinal nozzle slot 24 of the type disclosed in Patent No. 1,724,583, 35 granted August 13, 1929. This nozzle slot receives combusted gases from a combustion chamber 25, which is supplied with combustible gas and air or oxygen through the supply pipes 26, 27 respectively, the quantities of each being regulated by a hand controlled valve, not shown.

The operation of my improved multiple heat treatment furnace may be briefly described, with specific application to the multiple heat treatment of alloy steel. The alloy steel is first inserted into the preliminary heating furnace 11, where the temperature of the metal is raised to about 1600 degrees F. to impart an even heat thereto. The operator now reaches into the furnace 11, through the entrance opening 23, removes the heated metal and transfers it to the high temperature furnace 12, where it is heated to approximately 2350 degrees F.; as soon as the proper high temperature has been reached, the operator removes the highly heated metal from 50

furnace 12 and drops the same into the oil in quenching tank 21, this oil being preferably maintained at approximately 300 degrees F. These successive operations are carried out in a controlled atmosphere by directing combusted gases from the combustion chamber 25 upwardly through the nozzle slot 24 to effectively curtain the opening 23, the combusted gases impacting on the roof of the opening 23 to enter and fill the furnaces 11 and 12 and the passageway 13, as disclosed in Patent No. 1,724,583. The combusted gases are colorless, are transparent, do not interfere in any way with the movements of the operators in transferring treated metal from one furnace to the other or to the quenching tank, effectively exclude all atmospheric air from contact with the metal during the treatment and the movements thereof, and fill the furnace chambers and the passageway with an enveloping atmosphere of predetermined constituency. In the case of high speed steel, it is found desirable to maintain a slight excess of carbon monoxide in the enveloping atmosphere, which condition is readily obtained by suitable inspection means, for example, by observing a charcoal block indicator positioned in the high temperature furnace; as soon as the proportions of air and gases supplied to the combustion chamber insure complete combustion, the charcoal, which glows brightly whenever any oxygen is present, immediately becomes extinguished. The heat treatment may be continuous for successive batches of material to be heated, since the basket 22 in the quenching tank may be repeatedly emptied without disturbing the atmospheric air exclusion.

Under certain circumstances, it may be preferable to position additional nozzle slots in the throats 14 and 15, such as indicated in Figure 4, the additional slots being connected to the combustion chamber by means of valve controlled supply pipes (not shown); or individual combustion chamber slots and supply pipes may be installed for each furnace, as shown in Figure 4, thus obtaining either common or individual control of the enveloping atmosphere of the furnaces as desired. In addition, whenever very exact control of the constituency of the enveloping atmosphere in the high temperature or other furnace chamber is desired, a short outlet tube 50 of standard construction (not shown) having a pet cock therein may be run through the roof of the high temperature furnace, to permit periodic withdrawal of samples of the atmosphere therein, for testing purposes.

It will be noted that the use of a curtain of combusted gases is an advantageous feature for heating furnaces, since there is no rapid movement of gases in the furnace chamber, no introduction of gases at very different temperatures; the impacting of the combusted gases on the roof of the entrance opening produces a slow circulation of the enveloping atmosphere in the chamber without disturbing the heat distribution or the uniformity of heating therein.

Other changes in the structure and in the arrangement of the various furnaces, or in the procedure followed, may obviously be made to meet the requirements for heat treatment of specific materials, without departing from the spirit and scope of the invention as defined in the appended claims.

I claim:

1. In combination, a furnace chamber for preliminary heat treatment having a throat and otherwise closed, a furnace chamber for final heat

treatment having a throat, and otherwise closed, a passageway communicating said throats and having an entrance opening and otherwise closed, and means for maintaining atmospheres of regulated constituency in said chambers and passageway. 5

2. In combination, a furnace chamber for preliminary heat treatment having a throat and otherwise closed, a furnace chamber for high temperature heat treatment having a throat and otherwise closed, a passageway communicating said throats having an entrance opening and otherwise closed, a combustion chamber, and means for supplying products of combustion from said combustion chamber to form an atmosphere excluding curtain for said passageway opening. 10

3. In combination, a furnace chamber for preliminary heat treatment having a throat and otherwise closed, a furnace chamber for high temperature heat treatment having a throat and otherwise closed, a passageway communicating said throats having an entrance opening and otherwise closed, a combustion chamber, means for supplying products of combustion from said combustion chamber to form an atmosphere excluding curtain for said passageway opening, and means for diverting said curtain gases into said passageway to fill said passageway and said furnace chambers. 15

4. In combination, a furnace chamber for preliminary heat treatment having a throat and otherwise closed, a furnace chamber for final heat treatment having a throat and otherwise closed, a passageway communicating said throats and having an entrance opening, a quenching tank opening in the floor of said passageway, and means for excluding atmospheric air from said furnace chambers and passageway. 20

5. In combination, a furnace chamber for preliminary heat treatment having a throat and otherwise closed, a furnace chamber for final heat treatment having a throat and otherwise closed, a passageway communicating said throats and having an entrance opening, a quenching tank opening in the floor of said passageway, and means for maintaining atmospheres of regulated constituency in said furnace chambers and passageway. 25

6. In combination, a furnace chamber for preliminary heat treatment having a throat and otherwise closed, a furnace chamber for final heat treatment having a throat and otherwise closed, a passageway communicating said throats and having an entrance opening, a quenching tank opening in the floor of said passageway, a combustion chamber, and means for supplying products of combustion from said combustion chamber to form an atmosphere excluding curtain for said passageway opening. 30

7. In combination, a furnace chamber for preliminary heat treatment having a throat and otherwise closed, a furnace chamber for final heat treatment having a throat and otherwise closed, a passageway communicating said throats and having an entrance opening, a quenching tank opening in the floor of said passageway, a combustion chamber, means for supplying products of combustion from said combustion chamber to form an atmosphere excluding curtain for said passageway opening, and means for diverting said curtain gases into said passageway to fill said passageway and said furnace chambers. 35

8. In combination, a furnace chamber for preliminary heat treatment having a throat, a fur- 40

- nace chamber for high temperature heat treatment having a throat, a passageway communicating said throats having an entrance opening, a combustion chamber, and means for supplying 5 products of combustion from said combustion chamber to form an atmosphere excluding curtain for said passageway opening.
9. In combination, a furnace chamber for preliminary heat treatment having a throat, a furnace chamber for high temperature heat treatment having a throat, a passageway communicating said throats having an entrance opening, a combustion chamber, means for supplying products of combustion from said combustion 10 chamber to form an atmosphere excluding curtain for said passageway opening, and means for diverting said curtain gas into said passageway to fill said passageway and said furnace chambers.
- 15 10. In combination, a furnace chamber for preliminary heat treatment having a throat, a furnace chamber for final heat treatment having a throat, a passageway communicating said throats and having an entrance opening, a quenching tank opening in the floor of said 20 passageway, and means for excluding atmospheric air from said furnace chambers and passageway.
11. In combination, a furnace chamber for 25 preliminary heat treatment having a throat, a furnace chamber for final heat treatment having a throat, a passageway communicating said throats and having an entrance opening, a quenching tank opening in the floor of said 30 passageway, a combustion chamber, and means for supplying products of combustion from said 35
- combustion chamber to form an atmosphere excluding curtain for said passageway opening.
12. In combination, two furnace chambers for heat treatment having entrance throats, a passageway communicating said throats and having an entrance opening, and means for maintaining atmospheres of regulated constituency 5 in said chambers and passageway.
13. In combination, two furnace chambers for heat treatment having entrance throats, a passageway communicating said throats and having an entrance opening, and means for maintaining an atmosphere of regulated constituency 10 in each chamber and in the passageway.
14. In combination, two furnace chambers for heat treatment having entrance throats, a passageway communicating said throats and having an entrance opening, means for supplying products of combustion, and means for conveying 15 products of combustion from said supply means to form atmosphere excluding curtains for said entrance throats and said entrance opening.
15. In combination, two furnace chambers for heat treatment having entrance throats, a passageway communicating said throats and having an entrance opening, means for supplying products of combustion, means for conveying products of combustion from said supply means 20 to form atmosphere excluding curtains for said entrance throats and said entrance opening, and means for diverting the curtain gases adjacent the entrance throats and the entrance opening into the chambers and the passageway 25 to fill said chambers and said passageway. 30 35

CARL I. HAYES.
